UNITED STATES PATENT OFFICE.

JOHN L. MAUCH, OF LOS ANGELES, CALIFORNIA.

PHOTOGENIC COPYING APPARATUS.

1,251,076.

Specification of Letters Patent. Patented Dec. 25, 1917.

Application filed September 22, 1915. Serial No. 52,058.

To all whom it may concern:

Be it known that I, JOHN L. MAUCH, a citizen of the United States, residing at Los Angeles, in the county of Los Angeles and State of California, have invented or discovered certain new and useful Improvements in Photogenic Copying Apparatus, of which the following is a specification, reference being had therein to the accompanying drawings.

This invention relates to apparatus for producing photogenic copies of surfaces, such as writing, printing, designs, pictures etc., in accordance with the method which consists in interposing a transparent or translucent light-sensitive medium between the surface to be copied, and substantially in contact therewith, and a source of light, the rays from which pass through said sensitized medium to said surface, said rays being absorbed by the darker portions of said surface and being reflected from the lighter portions thereof into the sensitized medium again, whereby said medium will be affected to a greater degree at points adjacent the lighter portions of said surface than at points adjacent the darker portions thereof. More particularly the invention relates to photogenic apparatus of the general character shown and described in Letters Patent of the United States No. 1,097,120, granted May 19, 1914, to Henry H. Curtiss.

The invention has for its general object to improve the construction and arrangement of apparatus of this character and render the same more convenient, reliable, accurate and efficient in its operation and results.

The foregoing and other objects of the invention, together with means whereby the same may be carried into effect, will best be understood from the following description of one form or embodiment thereof illustrated in the accompanying drawing. It will be understood, however, that the particular construction described and shown has been chosen for illustrative purposes merely, and that the invention, as defined by the claims hereunto appended, may be otherwise practised without departing from the spirit and scope thereof.

In said drawings:—

Figure 1 is a substantially central transverse vertical section of the machine.

Fig. 2 is an end elevation, partly broken away, looking from the left in Fig. 3. 55

Fig. 3 is a vertical longitudinal section.

Fig. 4 is an end elevation of the machine as viewed from the right in Fig. 3.

Fig. 5 is a sectional view of the cap for closing the open mouth of the casing when the apparatus is not in use.

Fig. 6 is a partial front elevation, partly broken away.

Referring to Fig. 1, the body of the device comprises a main casing having an open lower end or mouth 11, closed, when the device is not in use, by a cap 19 (Fig. 5). 12 denotes a glass or other transparent or translucent roller journaled within the mouth 11 (see also Fig. 3), the lowermost portion of the surface of said roller being approximately flush with, or projecting slightly beyond the edges of said mouth. 13 and 14 denote spools or rollers rotatably mounted within the casing and upon which is wound a sensitized strip or film 15. The film 15 is withdrawn from the spool 13, passes about the roller 12, and is wound up on the spool 14. Suitable tension devices, hereinafter described, are provided whereby unwinding of the film from the spool 13, except as withdrawn by the roller 12, is yieldingly prevented, thereby maintaining a suitable tension between said spool and roller, and whereby said film, after leaving said roller, is immediately wound up on the spool 14 under a continuous tension. Within the lower part of the main casing is a lamp casing, designated as a whole by the numeral 16, and having an open lower end or mouth adjacent the roller 12. Supported within said lamp casing 16 is a suitable number (one or more) of electric lamps 17 supplied with current, through connections hereinafter described, from a battery or other source of electric energy 18.

In use the apparatus is placed with its open mouth 11 adjacent the surface 20 to be copied or photographed and with a portion of the film 15 interposed between said surface and the roller 12 and in contact with the former. As the device is moved over the surface 20 the film, gripped between said surface and the roller 12, is gradually withdrawn from the spool 13 and re-reeled upon the spool 14. As successive portions of said

film are thus presented to successive portions of the surface 20, light from the lamp or lamps 17 is transmitted through the roller 12 and film 15 to the surface 20, whence it is reflected to a greater or less extent back into said film, thereby causing said film to receive a photogenic impression of the portion of the surface traversed in accordance with the method above referred to.

10 The general organization and operation of the apparatus having thus been indicated, the construction of the various parts and mechanisms will now be described in detail.

The main casing is composed of end members 21 and 22 which are suitably grooved to receive the end edges of longitudinal members 23, 24 and 25, the latter being firmly clamped in position between the end members by means of bolts 26. The longitudinal member 24 forms the top and front of the casing. The upper and lower edges of the member 25 are received in suitable grooves or rabbets in the member 24, between which the corresponding portion of said member 24 is spaced from the member 25 to form a chamber or housing 27 for certain mechanism hereinafter described. The lower portion of the member 24 is spaced from the member 23, which forms the lower part of the back of the casing, the lower ends of said members 23 and 24 being separated to provide the open mouth 11. By this construction there is provided a simple, substantial, and light proof body or casing 35 which may be readily taken apart and assembled.

The upper portion of the back of the casing is formed by a cover 28 the end edges of which slide in grooves in the end members 21 and 22. The lower edge of said cover 28 is received in a groove in the upper edge of the member 23, while the upper edge of said cover is turned as shown at 29 (Fig. 1) to engage a groove or channel formed at the rear edge of the top portion of the member 24. Said cover 28 is normally held in the closed position shown in Fig. 1 by means of a movable catch 30 which, when released, permits said cover to be raised, thereby affording access to the interior of the casing for changing the film or sensitized strip, and for other purposes.

The casing is preferably provided at suitable points with observation windows 31 fitted with glass or other transparent medium of a suitable non-actinic color and provided with opaque covers 32, said windows being for the purpose of permitting observation of the strip or film. One of the windows 31 is preferably located at the top of the casing in such a position as to permit observation of the film on the spool 13, thereby determining the amount of unexposed film remaining on said spool. Another window is preferably provided in the

lower part of the member 24 to permit observation of the unexposed film between the spool 13 and the roller 12, or point of application to the surface 20.

The end members 21 and 22 are preferably provided with suitably formed projections and recesses 76, 77, 78 and 79 affording the operator a firm hold when pressing the machine upon and moving the same over the surface 20.

The transparent roller 12 is fitted at its ends with caps 33 and 34 (see Fig. 3) provided with studs rotatably mounted in the lower ends of the end members 21 and 22, respectively, whereby said roller is journaled in said members at the open mouth 11 of the casing, as above described. By the use of the roller 12 concentrated pressure is brought to bear upon the sensitized strip at the point where the light is concentrated, as hereinafter more fully explained, and good contact is thereby caused between the sensitized strip and the surface 20, such contact being essential to the production of a clear, sharp copy. Also by reason of the pressure exerted by the roller 12 considerable friction between the strip 15 and surface 20 is developed (the strip being tightly gripped between said roller and surface) which prevents these parts from slipping with reference to one another when the apparatus is moved over the surface. At the same time the roller 12 provides an anti-friction support for the sensitized strip with reference to the casing, and a rolling contact between the strip and surface, thereby further reducing the tendency of said strip to move with respect to the surface. It will of course be understood that, in order to secure a sharp and accurate copy it is necessary that said strip be held against slipping with respect to said surface at the time of exposure.

In order to obtain an evenly perfect copy it is necessary that the apparatus be moved over the surface 20 at a velocity not greater than a certain maximum, and that this velocity be uniform. For the purpose of thus controlling the speed of travel of the device the following mechanism is provided.

The cap 34 (see Fig. 3) at one end of the roller 12 has secured thereto or formed thereon a spiral gear 35 which meshes with a spiral gear 36 secured to an inclined shaft 37 journaled in a suitable bearing 38 (see also Fig. 4) formed on or secured to the end member 22. Secured to the upper end of the shaft 37 is a spiral gear 39 which meshes with a spiral gear 40 on a shaft 41 journaled in the end member 22 and in a bracket 42 (see Fig. 1) projecting from the casing member 25 within the housing 27. Secured to the shaft 41 is a second spiral gear 43 which meshes with a spiral gear 44 on the hub 46 of a fly wheel 45 (see also

Fig. 6), said hub and fly wheel being rigidly connected for rotation in unison. The hub 46 is rotatably mounted on a rod or axle 47 rigidly secured at its ends to the members 5 24 and 25 forming the walls of the housing 27.

By means of the gearing and connections last described, rotation of the fly wheel 45 is communicated to the roller 12, said fly 10 wheel being of a suitable weight to provide the necessary momentum or inertia effectively to control the velocity of rotation of said roller and consequently the speed of travel of the machine over the surface 20. 15 In order to set the fly wheel 45 and roller 12 in motion at a predetermined speed in accordance with the requirements the following mechanism is provided, reference being had particularly to Figs. 1 and 6. 20 48 denotes a shaft journaled at its inner end in a boss 49 on the casing member 25, said shaft having fixed to its outer end an arm or lever 50 located outside the casing and having a hub 51 journaled in a suitable 25 opening in the casing member 24. Fast on the shaft 48 is an arm 52 to which is secured one end of a spring 53 having its opposite end secured, as at 54, to the casing, said spring and arm acting normally to hold 30 the shaft 48 and parts thereon in the position shown in Fig. 6. 55 denotes a gear segment fast on the shaft 48 and adapted to mesh with a pinion 56 fast on the hub 46 of the fly wheel. 35 Movement of the arm or lever 50 from the position shown in Fig. 6 in the direction of the arrow on said figure causes the gear segment 55, which is normally out of engagement with the pinion 56, to engage 40 and turn the same, and also causes the spring 53 to be placed under tension. When the arm 50 is released and returns to normal position under the influence of the spring 53 rotation is imparted to the fly 45 wheel 45 through the pinion 56 and segment 55, the velocity imparted to said wheel depending upon the distance through which the arm 50 was initially moved. As the 50 arm 50 returns to normal position the segment 55 moves out of mesh with the pinion 56, permitting the fly wheel to continue its rotation, which rotation is communicated to the roller 12 as above explained.

As a convenient means for measuring the 55 distance through which the arm 50 is moved, and the consequent velocity imparted to the fly wheel, there is provided a segmental scale 57 over which said arm moves, said scale being secured to the exterior of the 60 front wall of the casing and having upwardly turned ends 58 to serve as stops for the arm.

59 denotes a brake shoe carried by a leaf spring 60 secured to the inside of the bottom 65 wall of the housing 27 and provided

with a button 61 projecting through said wall, whereby said brake shoe may be moved into engagement with the fly wheel 45 to stop the rotation thereof at will.

In order to insure the proper angular positioning of the fly wheel to permit engagement of the teeth of the segment 55 with the teeth of the pinion 56, when the arm 50 is moved to cause such engagement, the following mechanism is provided. 62 denotes 70 a positioning lever pivoted at 63 to the inner side of the front wall of the housing 27, the pivotal mounting of said lever being of such character as yieldingly to resist turning of said lever, so as to cause the same to 80 remain in any position into which it is turned, as by the provision of a spring washer 64. The lever 62 is provided with an operating stud 65 which projects through a short slot in the casing wall and by which 85 said lever may be turned on its pivot. At its free end the lever 62 is provided with a spring finger 66 adapted to engage and turn the pinion 56, when said lever is moved upwardly, and also with a stop shoulder 67 90 adapted to engage the lower edge of the pinion 56 to limit the upward movement of said lever. The arrangement is such that when the lever 62 is moved upwardly to the limit of its movement, determined by the engagement of the shoulder 67 with the pinion 56, the spring finger 66 will have turned said pinion into a proper angular position for engagement by the segment 55. The operating arm 50 is provided with a cam head 100 68 adapted, when said lever is moved, to engage the stud 65 and move the lever 62 into its normal position as shown in Fig. 6.

Prior to starting the machine the operator, by manipulation of the stud 65, moves the 105 lever 62 upwardly, thereby positioning the pinion 56 as above explained, the frictional character of the pivot 63 causing said lever to remain in its upper position and holding said pinion in the position in which it has 110 been turned. As the arm 50 is moved in the direction of the arrow on Fig. 6, and after the segment 55 has been brought into full engagement with the pinion 56, the cam head 68, by engagement with the stud 65, 115 depresses the lever 62, causing the finger 66 to release the pinion 56. Slight movement of the pinion 56 by the segment 55, prior to the complete depression of the lever 62 by the cam head 68, is permitted by the yielding mounting of the finger 66.

The lamp casing 16 (see Figs. 1 and 3) comprises a top section 69 and lower side sections 70, the ends of said sections being received in suitably formed grooves in the 125 end members 21 and 22. The top section 69 is composed of insulating material and is formed at its lower edges with grooved flanges 74 in which a lamp supporting plate 71, also of insulating material, is slidably 130

mounted. The flanges 74 are in turn received within channels 75 formed at the upper edges of the side sections 70, whereby said top and side sections are connected. 5 72 denotes lamp contacts carried by the top section 69 of the lamp casing, and 73 lamp sockets carried by the lamp supporting plate 71. As herein shown four lamps, lamp sockets, and lamp contacts are provided. The sockets 73 are all electrically connected with one another by a conductor 80. The two contacts 72 shown at the left in Fig. 3 are electrically connected or grounded to the end member 21 of the casing 10 by a conductor 81. The two contacts 72 at the right in Fig. 3 are electrically connected by a conductor 82 to a terminal 83 which passes through an insulating bushing 84 in the end member 22 and is provided outside 15 the casing with a binding post or equivalent connector 85 (see Fig. 4). To the binding post or connector 85 is connected one of the wires or terminals of the battery 18 the other wire or terminal of which is connected to a similar binding post or connector 86, also mounted 20 in the insulating bushing 84 and provided with a spring contact member 87. 88 denotes a circuit closer comprising a pin or plunger slidably mounted in a boss formed 25 on the end member 22 and adapted, when forced inwardly or toward the right in Fig. 4, to engage the contact member 87, thereby completing the circuit by grounding said contact member to the casing and consequently 30 electrically connecting the same through the casing with the conductor 81. 89 denotes a leaf spring normally holding the plunger 88 in circuit breaking position. The plunger 88 is provided with a head 35 90 preferably located adjacent one of the recesses 78, whereby said plunger may conveniently be held in circuit closing position against the tension of the spring 89 by the hand of the operator grasping the machine 40 when in use.

By providing a series of lamps 17, suitably spaced longitudinally of the lamp casing and consequently of the mouth or exposure opening 11, a proper uniform distribution of light is insured. Also, by thus disposing the light giving filament in a series of short units, probability of filament breakage, due to mechanical shocks to the apparatus, may be reduced to a minimum. 50

55 The side members or sections 70 of the lamp casing 16 extend downwardly and partly around the transparent roller 12, thereby preventing light from within said lamp casing from entering that portion of the main casing containing the exposed and unexposed film. Intermediate their upper and lower edges the side members or sections 70 are formed with grooves or channels 91 and 92 for supporting, respectively, 60 a light filter 93 and a lens 94, the ends of

which filter and lens are supported in suitably located grooves or recesses in the end members 21 and 22.

The light filter 91 is composed of glass or other transparent material of any suitable color in accordance with the requirements, and is for the purpose of obtaining greater contrast when copying inscriptions, designs or the like of various colors on variously colored surfaces. Also greater contrast can be obtained when copying black and white designs with certain kinds of sensitized strip by using a light filter of the proper color.

The lens 94 is of cylindrical form and operates with the transparent roller 12 in refracting the projected light so as to concentrate the light rays and cause them to fall upon the film 15 and surface 20 in the form of a relatively narrow strip of light of great brilliancy located at substantially the line of engagement of the film with the surface.

The end member 21 is provided with an opening 95 through which the lamp supporting plate 71 may be removed, by sliding the same in the grooves in the flanges 74, for the purpose of changing or replacing the lamps 17. Said end member 21 is further provided with a slot or opening 96 through which the light filter 93 may be removed, by sliding the same in its channels or guideways 91, whenever it may be desired to change filters. The openings 95 and 96 are closed by a cover 97 having adjacent its upper edge a hooked lug to engage the upper edge of the opening 95, said cover being retained in position by means of a pivoted catch 98 which engages a grooved stud 99 projecting from the end member 21 through a suitably located opening in said cover.

At the edges of the mouth 11 is a light seal designated as a whole by the numeral 100. Said light seal comprises a grooved attaching member or clip 101 conforming in shape to the edges of the mouth 11 and composed of resilient material, said attaching member having a covering 102 of plush or other soft, flexible, elastic, or yielding material adapted to exclude light without injury to the film 15 or surface 20, with both of which it comes in contact. The resilient clip or attaching member 101 detachably engages the edges of the walls of the opening 11, permitting the light seal to be removed from the machine for the purpose of facilitating the insertion of the film or sensitized strip and also for the purpose of renewing the covering 102 if the latter becomes worn or injured.

The light seal 100 comprises an edge portion *a*, an inner portion *b*, and an outer portion *c*. The portion *a* prevents extraneous light from striking that portion of the film 15 held in engagement with the surface 20

during the copying operation. The portion *b* prevents light from entering the main body of the casing and striking the sensitized strip within the same. The portion *c* co-operates with the cap 19 in preventing light from entering the machine when not in use and also, by reason of the yielding character of the covering 102, assists in retaining said cap in place, thereby preventing injury to the film from any cause.

The spools or rollers 13 and 14 comprise wooden or other suitable cores diametrically slotted to receive the ends of the film 15, whereby said film is attached to said cores, and provided adjacent their ends with flanges 103. As heretofore stated the un-exposed film is stored on the spool 13 from which said film passes to the roller 12, the exposed portion being subsequently wound upon the roller 14. For the purpose of obtaining sharp definition in the copy the film 15 is preferably so disposed that, in passing about the roller 12, the sensitized surface thereof will be downward or in engagement with the surface 20. Intermediate the roller 12 and spools 13 and 14 the film is guided at suitable points by certain of the bolts 26 and by guiding ribs or flanges 104 secured to or formed integral with the end members 21 and 22, said ribs or flanges facilitating the insertion of the film. The spools or rollers 13 and 14 are similar and interchangeable as will be familiar to those skilled in the art.

The spool 13 is rotatably mounted on pins or centers 106 which project through openings in the end pieces 21 and 22 and engage suitable axially disposed recesses in the ends of said spool. Said pins are normally held in engagement with the spool by means of flat springs 107 and are provided with suitable handles whereby they may be withdrawn for the purpose of releasing the spool. The spool 14 is rotatably supported at one end by a pin or center 108 similar to the centers 106 and is engaged at the opposite end by a dog 109, said spool and dog being connected for rotation in unison, as by forming the end of said spool with a diametric groove adapted to receive a flange or rib 110 on said dog. The dog 109 is rotatably and slidably mounted in a suitably disposed opening in the end member 21 and is fast upon a spindle 111 slidably and rotatably mounted in the wall of a housing 112 secured to the end member 21, as by means of screws 113. 114 denotes a spring interposed between the dog 109 and the wall of the housing 112 and normally holding said dog in operative engagement with the end of the spool 14. The spindle 111 is provided with a head 115 outside the housing 112 whereby the dog 109 may be withdrawn against the tension of the spring 114 in order to release the spool 14.

For the purpose of facilitating the insertion of the spools 13 and 14 the end members 21 and 22 are formed on their inner faces with projecting ledges or ribs 116 so formed and disposed as to act as guides and stops for positioning said spools with reference to the centers 106 and 108 and dog 109.

Within the housing 112 is a spring motor which, for the purposes of the present invention, may be of any usual or well-known type capable of applying a continuous turning force to a gear 127 which meshes with a pinion 128 mounted on the dog 109 for rotation therewith, thereby transmitting the force of the spring motor to the spool 14 in the form of a continuous torsional tension tending to wind up the film 15 on said spool. 122 denotes a winding post for the motor spring, said winding post being provided outside the motor housing with an operating key or knob 123. Preferably the connections are such as to permit winding of the motor spring without turning the gear 127, but as such connections are common in spring motors they are not shown in detail herein. The pinion 128 may, if desired, be held against retrograde movement, or movement in a direction to unwind the film, by a spring pressed pawl 129 pivoted on the interior of the housing 112 but preferably provided with an operating button 130 extending to the exterior of said housing, whereby said pawl may be released when desired.

117 denotes torsional springs preferably mounted on a convenient one of the bolts 26 and carrying a shoe 118 adapted to engage the roll of film on the spool 13, said shoe being covered or faced with a suitable material, such as plush, adapted to interpose a frictional resistance against the unwinding of the film from the spool 13 without injuring the face of said film. Said frictional resistance, while permitting a positive withdrawal of the film by the roller 12 when pressed against the surface 20, is preferably sufficient to neutralize or overcome the spring tension applied to the spool 14 by the spring motor.

In order to keep the tension of the spring motor within the limits necessary to prevent accidental withdrawal of the film 15 from the spool 13 against the resistance of the friction shoe 118, and at the same time to insure a torsional moment at least sufficient to wind up said film upon the spool 14 when positively withdrawn from the spool 13 by the roller 12 and subsequently released by the latter, there is provided a Geneva stop device comprising a wheel 137 mounted on a square portion of the winding post 122 and having a tooth periodically engaging a wheel 138 rotatably mounted on the housing 112. The wheel 138 rotates intermittently, advancing one segment for each rotation of 130

the wheel 137, and is preferably so constructed as to be limited in its rotation, as will be familiar to those skilled in the art. The segments of the wheel 138 may, if desired, be provided with numerals or other marks which pass a fixed mark on the housing 112 as the wheel rotates for the purpose of approximately indicating the number of rotations of the winding post 122 which have been made or which are still possible without rewinding.

The complete operation of the apparatus is as follows:

To load the device the slide or cover 28 and light seal 100 are removed and the casing turned with its back or open side up. The spool 13, having wound thereon the sensitized strip or film 15 (which preferably terminates at each end in a suitable length of attached non-sensitized strip) is inserted into the casing and engaged by the centers 106. The non-sensitized strip is sufficiently unwound to pass around the roller 12 to the spool 14, and this portion is so inserted, this operation being assisted by the guiding ribs 104. The free end of the strip having been passed through the slot in the spool 14, the latter spool is now inserted into the casing, and suitably engaged, at its opposite ends, by the center 108 and dog 109, respectively. If necessary the spool 14 is now turned, by means of the handle 115, in order to wind up the slack portion of the strip, and the slide 28 and light seal 100 are replaced.

The battery 18 having been connected to the apparatus, and the spring motor in the housing 112 having been wound, the fly wheel 45 and roller 12 are caused to rotate at a definite, uniform speed by pulling the lever 50 to the proper point on the scale 57 and releasing the same, as heretofore explained. The apparatus is now firmly grasped, the operator facing the front of the machine, or that side shown at the left in Figs. 1 and 2, with his thumbs resting in the depressions 76, and the middle finger of his right hand in the depression 78, and the middle finger of his left hand over the head 90 of the circuit breaker. The page or surface 20 to be copied being at hand, the apparatus, held in an erect position, is firmly pressed upon and passed over said page or surface, the head 90 of the circuit breaker at this time being depressed to close the circuit to the lamps 17, thus causing the light to be projected, through the light filter 93, lens 94, and roller 12, upon the page while the apparatus is being moved over the same.

During this movement the film or strip 15, gripped between the page and the roller 12, is gradually withdrawn from the spool 13 against the resistance of the friction shoe 118, and, when released by the roller 12, is immediately wound up upon the spool 14 under the influence of the spring motor. As

successive portions of the film are thus presented to successive portions of the page, said film is caused to receive a photogenic impression of the portion of the surface traversed, as heretofore explained. Should a certain portion of unexposed space be required on the film, in order to omit certain portions of the matter copied, or for the purpose of inscribing a title or other notes, it is only necessary to release the head 90 of the circuit breaker at the time of passing over such space.

It will of course be understood that the rate of travel of the apparatus over the page is controlled and rendered constant by the rate of rotation of the roller 12, which is in turn determined by the fly wheel 45, so that all portions of the strip are given a substantially uniform exposure. The tendency on the part of the operator should be to move the apparatus a little faster than the roller 12 travels, without, however, causing the strip to slip upon the page, but always maintaining a firm pressure, thus causing considerable frictional resistance against slipping, all for the purpose of aiding the fly wheel in maintaining its initial velocity by overcoming the frictional resistance in the gears or other connections by means of the manual power so supplied.

After the desired copy has been made the head 90 of the circuit breaker is released and the apparatus lifted from the page. Rotation of the fly wheel may now be stopped by applying brake 59 by means of the button 61, and the cover 19 placed over the mouth of the apparatus to protect the strip from injury and exclude extraneous light.

Having thus described my invention I claim and desire to secure by Letters Patent:

1. A photogenic copying machine comprising means for applying a sensitized strip to a surface to be copied, means for projecting light through said strip upon said surface, and means to obtain a substantially uniform exposure of said strip.

2. In a photogenic copying machine, means for applying a sensitized strip to a surface to be copied, said machine being movable over said surface to present successive portions of said strip to successive portions of said surface, and means for regulating the speed of travel of said machine over said surface.

3. In a photogenic copying machine, a roller for applying a sensitized strip to a surface to be copied and a fly wheel operatively connected with said roller.

4. In a photogenic copying machine, a roller for applying a sensitized strip to a surface to be copied, a fly wheel operatively connected with said roller, and means for stopping the rotation of said fly wheel.

5. In a photogenic copying machine, a roller for applying a sensitized strip to a

surface to be copied, a fly wheel operatively connected with the said roller, a pinion connected with said fly wheel, and a spring impelled gear segment coöperating with said pinion.

5. In a photogenic copying machine, a casing having an open mouth, a roller journaled in said casing at said mouth for applying a sensitized strip to a surface to be copied, a fly wheel within said casing and operatively connected with said roller, a pinion connected with said fly wheel, a spring impelled gear segment coöperating with said pinion, and an operating arm outside of said casing and connected with said gear segment.

6. In a photogenic copying machine, a roller for applying a sensitized strip to a surface to be copied, a fly wheel operatively connected with said roller, a pinion connected with said fly wheel, a spring impelled gear segment normally disengaged from said pinion but adapted to engage and turn the same, and means for angularly positioning said pinion for engagement by said segment.

10. In a photogenic copying machine, a roller for applying a sensitized strip to a surface to be copied, a fly wheel operatively connected with said roller, a pinion connected with said fly wheel, a spring impelled gear segment normally disengaged from said pinion but adapted to engage and turn the same, a lever, and a spring finger on said lever for angularly positioning said pinion for engagement by said segment.

15. In a photogenic copying machine, a roller for applying a sensitized strip to a surface to be copied, a fly wheel operatively connected with said roller, a pinion connected with said fly wheel, a spring impelled gear segment normally disengaged from said pinion but adapted to engage and turn the same, a lever, an operating stud for said lever, and a spring finger on said lever for angularly positioning said pinion for engagement by said segment.

20. In a photogenic copying machine, a roller for applying a sensitized strip to a surface to be copied, a fly wheel operatively connected with said roller, a pinion connected with said fly wheel, a spring impelled gear segment normally disengaged from said pinion but adapted to engage and turn the same, a lever, a frictional pivot for said lever, and a spring finger on said lever for angularly positioning said pinion for engagement by said segment.

25. In a photogenic copying machine a roller for applying a sensitized strip to a surface to be copied, a fly wheel operatively connected with said roller, a pinion connected with said fly wheel, a spring impelled gear segment normally disengaged from said pinion but adapted to engage and turn the same, means for angularly positioning said pinion for engagement by said segment, and

means for disengaging said positioning means and pinion.

30. In a photogenic copying machine, a roller for applying a sensitized strip to a surface to be copied, a fly wheel operatively connected with said roller, a pinion connected with said fly wheel, a spring impelled gear segment normally disengaged from said pinion but adapted to engage and turn the same, an operating arm for said segment, a lever, an operating stud for said lever, a spring finger on said lever for engaging and angularly positioning said pinion, and a cam head on said operating arm for engaging said stud to disengage said finger from said pinion.

35. In a photogenic copying machine, a roller for applying a sensitized strip to a surface to be copied, a fly wheel operatively connected with said roller, and operating means for said fly wheel adapted to cause rotation thereof at different predetermined speeds.

40. In a photogenic copying machine, a roller for applying a sensitized strip to a surface to be copied, a fly wheel operatively connected with said roller, operating means for said fly wheel, an operating arm for said operating means movable to different positions to cause rotation of said fly wheel at different speeds, and a graduated segment over which said arm is movable, said segment being provided with stops to limit the movement of said arm.

45. In a photogenic copying machine, a casing having an open mouth, a roller journaled in said casing at said mouth for applying a sensitized strip to a surface to be copied, a fly wheel within said casing and operatively connected with said roller, a pinion connected with said fly wheel, a spring impelled gear segment coöperating with said pinion, an operating arm for said segment outside said casing, and a graduated segment secured to the exterior of said casing and over which said arm is movable, said segment being provided with stops to limit the movement of said arm.

50. A photogenic copying machine comprising means for applying a sensitized strip to a surface to be copied and for producing a rolling contact between said strip and surface, and means for projecting light through said strip upon said surface.

55. A photogenic copying machine comprising a transparent roller for applying a sensitized strip to a surface to be copied and means for projecting light through said roller and strip upon said surface.

60. A photogenic copying machine comprising means for applying a sensitized strip to a surface to be copied, a source of light, and a lens interposed between said source of light and said strip.

65. A photogenic copying machine com-

- prising a transparent roller for applying a sensitized strip to a surface to be copied, a source of light, and a lens interposed between said source of light and said roller.
5. 20. A photogenic copying machine comprising means for applying a sensitized strip to a surface to be copied, a source of light, and a light filter interposed between said source of light and said strip.
10. 21. A photogenic copying machine comprising a casing provided with means for applying a sensitized strip to a surface to be copied, a source of light within said casing, and a light filter within said casing between said source of light and said strip, said casing having an opening to permit the removal of said filter.
15. 22. A photogenic copying machine comprising a casing provided with means for applying a sensitized strip to a surface to be copied and a source of light within said casing, said casing being provided with an opening to permit the removal of said source of light.
20. 23. A photogenic copying machine comprising a casing provided with means for applying a sensitized strip to a surface to be copied, a source of light within said casing, a light filter within said casing between said source of light and said strip, said casing having an opening to permit the removal of said source of light and an opening to permit the removal of said filter, and a common cover for both of said openings.
25. 24. A photogenic copying machine comprising a casing provided with means for applying a sensitized strip to a surface to be copied, a lamp supporting plate slidably mounted in said casing, and one or more lamps carried by said plate, said casing being provided with an opening to permit the removal of said plate.
30. 25. A photogenic copying machine comprising means for applying a sensitized strip to a surface to be copied and a plurality of spaced electric lamps for projecting light upon said strip and surface.
35. 26. A photogenic copying machine comprising a main casing having an open mouth, a transparent roller journaled in said casing at said mouth for applying a sensitized strip to a surface to be copied, a lamp casing within said main casing and having a portion partially inclosing said roller, and a source of light within said lamp casing.
40. 27. A photogenic copying machine comprising a main casing provided with means for applying a sensitized strip to a surface to be copied, a lamp casing within said main casing, a source of light within said lamp casing, and a lens supported by said lamp casing between said source of light and said strip.
45. 28. A photogenic copying machine comprising a main casing provided with means
- for applying a sensitized strip to a surface to be copied, a lamp casing within said main casing, a source of light within said lamp casing, and a light filter supported by said lamp casing between said source of light and said strip.
50. 29. A photogenic copying machine comprising a main casing having an open mouth, a transparent roller journaled in said casing at said mouth for applying a sensitized strip to a surface to be copied, a lamp casing within said main casing and having a portion partially inclosing said roller, a source of light within said lamp casing, and a lens and a light filter supported by said lamp casing between said source of light and said strip.
55. 30. A photogenic copying machine comprising means for applying a sensitized strip to a surface to be copied, an electric lamp for projecting light through said strip upon said surface, and a manually operated circuit controller for said lamp operable to control the circuit to said lamp independently of the application of said strip to said surface.
60. 31. A photogenic copying machine comprising a casing provided with means for applying a sensitized strip to a surface to be copied and means within said casing for winding said strip, said casing being provided with flanges or ribs for guiding said strip between said applying means and said winding means.
65. 32. A photogenic copying machine comprising a casing having an open mouth, means located at said mouth for applying a sensitized strip to a surface to be copied, means within said casing for projecting light upon said strip, and a light seal surrounding said mouth and engaging said surface for preventing extraneous light from striking the portion of said strip in engagement with said surface.
70. 33. A photogenic copying machine comprising a casing having an open mouth, means located at said mouth for applying a sensitized strip to a surface to be copied, means within said casing for projecting light upon said strip, and a light seal surrounding said mouth and engaging said surface for preventing extraneous light from striking the portion of said strip in engagement with said surface, said light seal having a covering of soft, elastic material to prevent injury to said surface.
75. 34. A photogenic copying machine comprising a casing having an open mouth, means located at said mouth for applying a sensitized strip to a surface to be copied, means within said casing for projecting light upon said strip, and a light seal adjacent said mouth and engaging said strip, said light seal having a covering of soft elastic material to prevent injury to said strip.
80. 35. A photogenic copying machine comprising a main casing having an open mouth, a transparent roller journaled in said casing at said mouth for applying a sensitized strip to a surface to be copied, a lamp casing within said main casing and having a portion partially inclosing said roller, a source of light within said lamp casing, and a lens supported by said lamp casing between said source of light and said strip.
85. 36. A photogenic copying machine comprising a main casing having an open mouth, a transparent roller journaled in said casing at said mouth for applying a sensitized strip to a surface to be copied, a lamp casing within said main casing and having a portion partially inclosing said roller, a source of light within said lamp casing, and a lens supported by said lamp casing between said source of light and said strip.
90. 37. A photogenic copying machine comprising a main casing having an open mouth, a transparent roller journaled in said casing at said mouth for applying a sensitized strip to a surface to be copied, a lamp casing within said main casing and having a portion partially inclosing said roller, a source of light within said lamp casing, and a lens supported by said lamp casing between said source of light and said strip.
95. 38. A photogenic copying machine comprising a main casing having an open mouth, a transparent roller journaled in said casing at said mouth for applying a sensitized strip to a surface to be copied, a lamp casing within said main casing and having a portion partially inclosing said roller, a source of light within said lamp casing, and a lens supported by said lamp casing between said source of light and said strip.
100. 39. A photogenic copying machine comprising a main casing having an open mouth, a transparent roller journaled in said casing at said mouth for applying a sensitized strip to a surface to be copied, a lamp casing within said main casing and having a portion partially inclosing said roller, a source of light within said lamp casing, and a lens supported by said lamp casing between said source of light and said strip.

35. A photogenic copying machine comprising a casing having an open mouth, means located at said mouth for applying a sensitized strip to a surface to be copied, means within said casing for projecting light upon said strip, and a light seal adjacent said mouth and detachably connected with said casing.

36. A photogenic copying machine comprising a casing having an open mouth, means located at said mouth for applying a sensitized strip to a surface to be copied, means within said casing for projecting light upon said strip, and a light seal adjacent said mouth and engaging said strip, said light seal being detachably connected with said casing to facilitate the insertion of said strip.

37. A photogenic copying machine comprising a casing having an open mouth, means located at said mouth for applying a sensitized strip to a surface to be copied, means within said casing for winding said strip, means within said casing for projecting light upon said strip, and a light seal adjacent said mouth and engaging said strip, said light seal being detachably connected with said casing and said casing being provided with flanges or ribs for guiding said strip between said applying means and said winding means to facilitate the insertion of said strip.

38. A photogenic copying machine comprising a casing having an open mouth, means located at said mouth for applying a sensitized strip to a surface to be copied, means within said casing for projecting light upon said strip, and a light seal adjacent said mouth, said light seal comprising a grooved attaching member conforming in shape to the edges of said mouth, composed of resilient material, and having a covering of soft, elastic material.

39. A photogenic copying machine comprising a casing having an open mouth, means located at said mouth for applying a sensitized strip to a surface to be copied, and a movable cap for closing said mouth for protecting the portion of said strip adjacent thereto when said machine is not in use.

40. A photogenic copying machine comprising a casing having an open mouth, means located at said mouth for applying a sensitized strip to a surface to be copied, a movable cap for closing said mouth for protecting the portion of said strip adjacent thereto when said machine is not in use, and a light seal surrounding said mouth and operating with said cap.

41. In a photogenic copying machine, a casing, rollers within said casing for winding a sensitized strip, means for rotatably supporting said rollers, and guide ribs on the interior of said casing for facilitating

the insertion of said rollers into operative position with respect to said supporting means.

42. In a photogenic copying machine, means for applying successive portions of a sensitized strip to successive portions of a surface to be copied, a spool or roller upon which the unexposed portion of said strip is wound, and means to resist turning of said spool or roller to unwind said strip.

43. In a photogenic copying machine, means for applying successive portions of a sensitized strip to successive portions of a surface to be copied, a spool or roller upon which the unexposed portion of said strip is wound, and a spring pressed friction shoe engaging the strip on said spool or roller, said shoe being covered with a soft material to prevent injury to said strip.

44. In a photogenic copying machine, means for applying successive portions of a sensitized strip to successive portions of a surface to be copied, a spool or roller on which the exposed portion of said strip is wound, and means for preventing rotation of said roller in a direction to unwind said strip.

45. In a photogenic copying machine, means for applying successive portions of a sensitized strip to successive portions of a surface to be copied, a spool or roller on which the exposed portion of said strip is wound, a pinion operatively connected with said roller, and a pawl coöperating with said pinion for preventing rotation of said roller in a direction to unwind said strip.

46. In a photogenic copying machine, means for applying successive portions of a sensitized strip to successive portions of a surface to be copied, a spool or roller on which the exposed portion of said strip is wound, a pinion operatively connected with said roller, a pawl coöperating with said pinion for preventing rotation of said roller in a direction to unwind said strip, and means whereby said pawl may be disengaged from said pinion.

47. In a photogenic copying machine, means for applying successive portions of a sensitized strip to successive portions of a surface to be copied, a spool or roller on which the exposed portion of said strip is wound, and means for applying a continuous turning force to said spool or roller tending to wind up said strip.

48. In a photogenic copying machine, means for applying successive portions of a sensitized strip to successive portions of a surface to be copied, a spool or roller upon which the unexposed portion of said strip is wound, means to resist turning of said spool or roller to unwind said strip, a second spool or roller on which the exposed portion of said strip is wound, and means for applying a continuous turning force to said last-

named spool or roller tending to wind up said strip.

49. A photogenic copying machine comprising a transparent roller for applying successive portions of a sensitized strip to successive portions of a surface to be copied, means for projecting light through said roller and strip upon said surface, a spool or roller upon which the unexposed portion 10 of said strip is wound, means to resist turning of said spool or roller to unwind said strip, a second spool or roller on which the exposed portion of said strip is wound, and means for applying a continuous turning force to said last-named spool or roller tending to wind up said strip.

50. In a photogenic copying machine, means for applying successive portions of a sensitized strip to successive portions of a 20 surface to be copied, a spool or roller on which the exposed portion of said strip is wound, and a manually wound spring and connections for applying a continuous turning force to said spool or roller tending to 25 wind up said strip.

51. In a photogenic copying machine, means for applying successive portions of a sensitized strip to successive portions of a surface to be copied, a spool or roller on 30 which the exposed portion of said strip is wound, a spring, connections intermediate said spring and roller for winding said spring and for applying a continuous turning force to said spool or roller tending to wind up 35 said strip, said connections permitting said spring to be wound without turning said spool or roller.

52. In a photogenic copying machine, means for applying successive portions of a 40 sensitized strip to successive portions of a surface to be copied, a spool or roller on which the exposed portion of said strip is wound, means for preventing rotation of said spool or roller in a direction to 45 wind said strip, a spring, connections inter-

mediate said spring and roller for winding said spring and for applying a continuous turning force to said spool or roller tending to wind up said strip, said connections permitting said spring to be wound without turning said spool or roller.

53. In a photogenic copying machine, means for applying successive portions of a sensitized strip to successive portions of a surface to be copied, a spool or roller on 55 which the exposed portion of said strip is wound, a manually wound spring and connections for applying a continuous turning force to said spool or roller tending to wind up said strip, and means to indicate 60 the available energy of said spring.

54. In a photogenic copying machine, means for applying successive portions of a sensitized strip to successive portions of a surface to be copied, a spool or roller on 65 which the exposed portion of said strip is wound, a manually wound spring and connections for applying a continuous turning force to said spool or roller tending to wind up said strip, and means for limiting the 70 minimum and maximum tension of said spring.

55. In a photogenic copying machine, means for applying successive portions of a sensitized strip to successive portions of a 75 surface to be copied, a spool or roller on which the exposed portion of said strip is wound, a manually wound spring and connections for applying a continuous turning force to said spool or roller tending to wind 80 up said strip, a Geneva stop device comprising a wheel rotated by said spring and a second wheel intermittently rotated by said first-named wheel, said second wheel being provided with a series of reference 85 marks, and a fixed member having a reference mark adjacent said second wheel.

In testimony whereof I affix my signature.

JOHN L. MAUCH.
